(57) **CLAIM**

The ornamental design for a tiny house, as shown and described.

DESCRIPTION

FIG. 1 is a front perspective view of my design for a tiny house,

FIG. 2 is a back perspective view thereof,

FIG. 3 is a front side elevation view thereof,

FIG. 4 is a right side plan view thereof

FIG. 5 is a left side plan view thereof,

FIG. 6 is a top side plan view thereof; and,

FIG. 7 is a bottom side view thereof.

In the drawings, the front side is mirror image to the back side, and the broken lines are for the purpose of illustrating environment only and form no part of the claimed design.
